[57] CLAIM

The ornamental design for a seat mount, as shown and described.

DESCRIPTION

FIG. 1 is a top perspective view of the seat mount showing my new design;

FIG. 2 is a top plan view thereof;

FIG. 3 is a front elevational view thereof;

FIG. 4 is a right side elevational view, the left side being a mirror image thereof;

FIG. 5 is a bottom plan view thereof; and

FIG. 6 is a rear elevational view thereof.
